FRANCIS L. PALMER, SR., OF NEW YORK, N. Y.

Letters Patent No. 98,101, dated December 21, 1869.

IMPROVED PACKING AND ATOMIZING-CAN FOR INSECT-POWDER.

The Schedule referred to in these Letters Patent and making part of the same.

To all whom it may concern:

Be it known that I, FRANCIS L. PALMER, Sr., of the city, county, and State of New York, have invented a new and improved Packing and Atomizing-Can; and I do hereby declare that the following is a full, clear, and exact description thereof, which will enable others skilled in the art to make and use the same, reference being had to the accompanying drawings, forming part of this specification.

This invention relates to improvements in cans for packing insect-powder, and other like finely-powdered substances, which, in use, require to be delivered in atomic jets, for penetrating crevices, where insects secrete themselves; and

It consists in providing such cans with stoppers having nozzles, through which stoppers or nozzles the passages are temporarily closed, in a way to be readily opened for use; also, in providing the cans with nozzles at or near the bottom, temporarily plugged, in which tubes may be connected, so that the powder may, when required for use, be readily blown out in atomic jets, whereby the said cans are made to subserve the uses of packing-cans and discharging atomizing-cans, with but trifling additional expense; whereas, at the present time, users of such powders are compelled to buy expensive atomizing-cans, to which the powder must be transferred from the packing-cans, before it can be properly used, or, in the absence of such cans, the powder is scattered in an ineffectual and wasteful way, in or about the resorts of the insects.

The drawing represents an elevation (partly broken out) of my improved can and its adjuncts.

A is a packing-can, which may be made of any suitable substance, and in any approved form adapted for holding the powder for storage, transportation, or use.

It is provided with a nozzle, B, at the top, of ordinary construction, for the reception of a stopper, C,

which may be of cork, or other substance which may be readily cut or broken.

In this stopper I place, when the can is filled and prepared for market, a small tube or nozzle, D, passing nearly, but not quite, through its vertical axis, so that when the powder is required for use, the stopper being removed, may be cut or otherwise separated on the line E, to open the passage through the nozzle D, for the discharge of the powder, the stopper, together with the nozzle, being replaced in the can.

At or near the bottom of the can, I make another nozzle, F, and plug it with a cork or other stopper, when the can is filled, which plug may be removed for the insertion of a tube, G, with a cork stopper, H, at the end, so that by blowing through the tube, the powder will be discharged in a jet at the nozzle D.

These tubes G may be made of cane, reed, bamboo, or other suitable cheap substances, which may be readily prepared, and they, together with their corks or stoppers, may be prepared and packed in the boxes with the cans, one or more for each to be supplied with the said cans; or they may be provided separately.

Having thus described my invention,

I claim as new, and desire to secure by Letters Patent—

1. A packing-can for insect and other powder, provided with the nozzle F, at or near the bottom, and a stopper, C, containing a nozzle, arranged in the same, substantially as specified.

2. The combination with the above of a tube, C, and plug H, arranged as described, for attachment to the nozzle F, as specified.

The above specification of my invention signed by me, this 6th day of September, 1869.

FRANCIS L. PALMER, SR.
